UNITED STATES PATENT OFFICE.

CHESTER L. LANDIS, OF READING, PENNSYLVANIA.

HOSIERY-MACHINE YARN-TENSION DEVICE.

Application filed May 13, 1926. Serial No. 108,842.

This invention relates to take-up adjustments for knitting machines and more particularly to stocking knitting machinery and its object is to provide a cam plate that may be secured to a wheel constantly rotating and adapted to oscillate a lever having an anti-friction roller at one end for engagement by the cams and a rod and hook at the opposite end adapted to catch the yarn as it passes from the spool to the knitting needles and by its reciprocating movement to keep the yarn taut so that the slack will not catch in other parts of the machine or would twist or knot unless properly disposed of.

These and other objects and details of the invention are more fully described in the following specification, set forth in the appended claim and illustrated in the accompanying drawings, wherein:

Fig. 1 is a side elevation of a stocking knitting machine, showing the improvement applied thereto.

Fig. 2 is a detail view of the cam plate from its inner side.

Fig. 3 is an edge view of said cam plate.

Fig. 4 is a detail view of the operating lever.

Only so much of the knitting machine is shown in Fig. 1 as is necessary to illustrate the application and operation of the improved take-up which consists of a cam plate 10 that is secured to a wheel or head 11 on the shaft 12, that forms parts of the stocking machinery in common use.

As will be more clearly seen in Figs. 2 and 3, the plate 10 is spaced away from the face of wheel 11 by studs 13 at the rear of the cam plate, but held rigid with the wheel by means of bolts 14 that pass through slots 30 and into the wheel 11 and their passageway in the cam plate consists of slots 15 that permit of a delicate adjustment of the cam to effect the operation of the take-up mechanism at the proper time.

The cam 10 has two faces that cause a take-up and retention movement; the face 16 being shorter than the face 17, it follows that its operation will occupy much less time than the face 17.

Upon the above-described faces is adapted to run a roller 18 carried at the end of a lever 19, that is pivoted at the frame of the knitting machine at 20, and has various

perforations 21 so it may be adjusted on the pivot to provide more or less leverage.

At the outer end of the lever 19 is secured a link 22 that carries at its upper end the rod 23 having the hook 24 at its extremity to catch the yarn Y as it passes from its spool to the needles and is held taut until needed.

The yarn Y is released when the roller 18 reaches the interval between the two cam faces, and these intervals occur twice during the rotation of the wheel 10, and are of the same length.

As shown in Fig. 1, the yarn is held taut, but as the wheel 11 rotates in the direction indicated by the arrow, the roller 18 will drop into the interval between the two cam faces 16 and 17, when the hook 24 will ascend and the consequent slack in the yarn will permit of its being fed into the needles, after which the roller will ride up the inclined end of face 17, and the hook will again be brought down.

A coil spring 25 secured to the lever at one end and to the frame of the machine at the other end, tends to keep that part of the lever and the hook 25 in its elevated position and to throw the roller 18 against the cam faces.

By this simple device, that may be readily applied to a knitting machine at some rotating part, the yarn may readily be taken up, and fed out automatically without any further care or attention.

It is obvious that the parts may be otherwise arranged or modified without departing from the essential features above described, or from the scope of the appended claim.

What I claim is:

In taking up mechanism for a knitting machine, the combination of rotating means connected with said knitting machine, a disc with cam faces and slots adapted to be 95 adjustably secured to said rotating means, a lever pivoted to the said machine, a roller carried at one end of the lever and adapted to play on the faces of the cam disc, a link at the other end of the lever, a hooked rod 100 carried by the link, and bolts passing through the slots to secure the disc to the rotating means.

In testimony whereof I hereunto affix my signature.

CHESTER L. LANDIS.
